(57) **CLAIM**

The ornamental design for a tie-down swivel, as shown and described.

DESCRIPTION

FIG. 1 is a perspective view of a tie-down swivel in accordance with my invention;

FIG. 2 is a top plan view of the tie-down swivel shown in FIG. 1;

FIG. 3 is a bottom plan view of the tie-down swivel shown in FIG. 1;

FIG. 4 is a right side view of the tie-down swivel shown in FIG. 1;

FIG. 5 is a left side view of the tie-down swivel shown in FIG. 1;

FIG. 6 is a left end view of the tie-down swivel shown in FIG. 1;

FIG. 7 is a right end view of the tie-down swivel shown in FIG. 1;

FIG. 8 is another perspective view of the tie-down swivel shown in FIG. 1 shown with additional context;

FIG. 9 is yet another perspective view of the tie-down swivel shown in FIG. 1 shown with additional context;

FIG. 10 is another perspective view of the tie-down swivel shown in FIG. 1 in a different context;

FIG. 11 is a top plan view of the tie-down swivel shown in FIG. 9;

FIG. 12 is a bottom plan view of the tie-down swivel shown in FIG. 9;

FIG. 13 is a right side view of the tie-down swivel shown in FIG. 9;

FIG. 14 is a left side view of the tie-down swivel shown in FIG. 9;

FIG. 15 is a left end view of the tie-down swivel shown in FIG. 9;

FIG. 16 is a right end view of the tie-down swivel shown in FIG. 9;

FIG. 17 is another perspective view of the tie-down swivel shown in FIG. 9 shown with additional context; and,

FIG. 18 is yet another perspective view of the tie-down swivel shown in FIG. 9 also shown with additional context.

The broken line showing of the tie down swivel is included for the purpose of illustrating portions of the article and forms no part of the claimed design.
